UNITED STATES PATENT OFFICE.

FREDERICK LEPPE AND WILLIAM H. MAVITY, OF ST. LOUIS, MISSOURI.

TUNING DEVICE FOR SAXOPHONES.

Application filed November 29, 1922. Serial No. 603,932.

This invention relates to improvements in a tuning device for saxophones, and has for its object a telescopic mechanism arranged between the mouth-piece and the neck of the instrument, which mechanism can be adjusted in order to regulate the proper tone.

A further object of our invention is to construct a tuning means which consists of a tubular socket mechanism attached to the neck of the instrument and a tubular insert slide tube attached to the mouth-piece, both so arranged so as to be singly fitted one within the other, making a leak-proof connection at any adjustment in which the slide tube is inserted. The inner surface of the slide tube is so swaged and tapered as to provide a free passage of the wind from the mouth-piece to the instrument, thus preventing the formation of a whirl-wind in the mouthpiece; and a clamping means by which the mechanism is held in its proper tuned adjustment.

The mechanism is simple in construction but has overcome the objectionable features of the old and present style of connection between the neck and the mouth-piece, which is in the form of a tapered cork placed over the neck, and of a construction as that shown in Fig. 7 of the drawings. By this tapered connection the mouth-piece must be tightly forced on to the cork or otherwise the same becomes wobbly.

Figure 1, is a side elevation of our invention.

Fig. 2, is a bottom plan view of the same.

Fig. 3, is a central sectional view.

Figs. 4 and 5, are detail perspective views showing our invention ready to be inserted one within the other.

Fig. 6, is a combination side and sectional view showing the mode of adjustment.

Fig. 7, is a combination side and sectional view of a mouth-piece and neck of the old-style connection.

Referring to the drawings in detail 8 indicates the neck of a saxophone or similar wind instrument, 9 is the mouth-piece, and in said mouth-piece we provide an extension 10 which is preferably of a tubular structure, the same being tightly held in the mouth-piece, and the inner end of said extension is swaged outwardly as indicated by the numeral 11 so there is formed a thin or feather edge at this end of the extension and thus

by this formation it prevents an off-set or shoulder at that point such as is shown by the numeral 12 in the old-style formation Fig. 7.

This off-set in the old-style causes the wind to strike an edge and passes the wind in circular formation such as a whirl-wind and does not allow it to pass freely and un-interrupted into the instrument. By the tapered swaged formation as shown in Fig. 3, the wind from the mouth passes freely and un-interrupted through the tubular extension and into the instrument. This end of the tubular extension 10 is fixedly inserted in the mouth piece of the instrument.

The extension 10 projects a considerable length beyond the mouth-piece and it is designed to be inserted in the sleeve or socket 13 attached to the end of the neck 8, and firmly held in position by the band or cover 14.

The joining edges of the sleeve and neck are arranged to butt one against the other making a free un-interrupted passage.

The inner surface of the free end 15 of the tubular extension is tapered as that shown by the numeral 16 down to the feather edge thus allowing the wind to pass from the extension un-interrupted into the instrument.

On the free end of the sleeve 13 we provide a clamping means consisting preferably of a band 17 and rigidly connected to the sleeve at one point, allowing the arms and unfastened members of the band sufficient freedom as to create a clamping action against the sleeve when the arms are brought together by means of the tightening screw 18. In order to allow for this gripping feature a portion of the sleeve is slit as that indicated by the numeral 19.

By inserting or partially removing the sliding tubular extension from the socket the tone of the instrument is governed, and in Fig. 6 we illustrate the various positions the extension may assume in the sleeve.

By this tubular arrangement of adjustment the mouth-piece is at all times rigid, whereas in the old-fashioned method when the mouth-piece is partially pulled away from the cork-tip the same is loose and does not produce the proper result.

Having fully described our invention what we claim is:

1. A tuning device for saxophones and similar instruments, comprising a sleeve car-

ried by the neck of the instrument, a tubular extension adapted to fit into the said sleeve, carried by the mouth-piece of the instrument, said sleeve and extension having close telescopic connection with each other, the inner end of the said extension being internally tapered to form a thin feather edge, and such end being fixed in the mouth piece, whereby there is an uninterrupted smooth wind passage from the mouth piece into and through the extension.

2. A tuning device of the class described comprising a tubular extension carried by the mouth-piece, a sleeve carried by the neck of the instrument, both so arranged as to provide telescopic connection, the extension ends of the nipple being tapered to

feather edges for un-interrupted wind passage, and a clamping means for holding the sleeve and tubular extension in positive connection when adjusted to insure the proper tone, substantially as specified.

3. A tuning device for saxophones comprising an adjustable positive telescopic connection located between the mouth-piece and the neck of the instrument, the same having its ends tapered to feather edges for providing a free smooth un-interrupted passage for the wind from the mouth to the instrument.

In testimony whereof, we have signed our names to this specification.

FREDERICK LEPPE.
WILLIAM H. MAVITY.
